UNITED STATES PATENT OFFICE.

GEORGE H. RANDALL, OF FORESTVILLE, MARYLAND, ASSIGNOR TO HIMSELF AND WILLIAM H. WOODS, OF SAME PLACE.

IMPROVEMENT IN COMBINED ATMOSPHERIC EXHAUST PUMPS AND FUNNELS.

Specification forming part of Letters Patent No. **136,264**, dated February 25, 1873.

To all whom it may concern:

Be it known that I, GEORGE H. RANDALL, of Forestville, in the county of Prince George's and State of Maryland, have invented a new and Combined Atmospheric Exhaust Pump and Funnel; and I do hereby declare the following to be a full, clear, and exact description of the same, reference being had to the accompanying drawing forming a part of this specification.

The invention relates generally to funnels through which liquids are poured into vessels, but more particularly to those used with sirup, molasses, and other viscous fluids. The invention consists in making funnels with an external sleeve, closely joined to the funnel-body, and extending down the nozzle for a sufficient distance to enable its end to reach within the jug, demijohn, barrel, cask, or other receptacle for the liquid, and in connecting the chamber thus formed between nozzle and sleeve with an air-exhaust pump, as hereinafter fully described and subsequently claimed.

The figure represents a vertical section.

In the drawing, A represents an ordinary funnel having body *a* and nozzle *a'*. B is a sleeve, soldered to the funnel-body at *b* and extending down the nozzle *a'* far enough to reach within the vessel to be filled. This forms an air-tight channel-way, *b'*, between

the nozzle *a'* and the sleeve B. With this channel-way *b'* is conjoined a neck, *c*, of the air-exhaust pump C, which is preferably soldered to the funnel at two points, *c¹* *c²*. D is the piston, which is operated by a hand-rod, *d*.

The application is as follows: The funnel A is placed with its nozzle and sleeve within the vessel which is to be filled and the sirup or other liquid then poured into the funnel. The atmospheric pressure above the funnel and below the nozzle being equal gravity is the only force used to carry the viscous liquid into the receptacle; and as this is barely sufficient to overcome the cohesive attraction between the particles of the mass in the funnel the inflow is very slow and tedious.

By my invention, as soon as the funnel is filled with sirup, I exhaust the air from vessel and thereby remove its counter-pressure, thus utilizing the outside atmosphere to force the sirup rapidly into the receptacle.

Having thus described my invention, what I claim as new, and desire to secure by Letters Patent, is—

The combination of an air-exhaust pump with a funnel for liquids, as and for the purpose described.
